A mounting means for operatively mounting one or more glass shower door panels to one or more panels is described. The mounting means includes an elongate guide assembly adapted for receiving and retaining a carriage assembly for mounting a reciprocating glass shower door; and a mounting assembly including one or more end mounting devices for mounting one or more ends of the elongate guide assembly perpendicular to one or more glass panels or walls. Also described is a mounting means including an elongate guide assembly adapted for receiving and retaining a carriage assembly for mounting a reciprocating glass shower door; and one or more spaced guide mounting devices for connecting the guide assembly to an adjacent parallel panel and spacing the guide assembly a selected distance from and parallel to the adjacent parallel glass wall panel to provide access between the parallel glass wall panel and guide assembly for cleaning.

DOOR MOUNTING ASSEMBLIES

CROSS-REFERENCE TO RELATED
APPLICATIONS

This application is related to and claims priority to U.S. Provisional Patent Application Ser. No. 60/740,106 filed Nov. 28, 2005, U.S. Provisional Patent Application Ser. No. 60/791,273 filed Apr. 12, 2006, and is a Continuation of U.S. Design application Ser. No. 29/247,024 filed May 24, 2006, the entirety of which are incorporated herein.

FIELD OF THE INVENTION

The subject application relates generally to mounting assemblies for sliding doors. One particular application for the subject application involves mounting frameless glass doors, associated with showers. Although it will be convenient to describe the subject application with reference to the abovementioned particular application, it is to be understood that this is not to be taken as a limitation of the scope of the subject application.

BACKGROUND OF THE INVENTION

It is known to provide sliding doors to control access to rooms of one type or another including shower recesses, however with current mounting assemblies and hardware it is difficult to maintain the mounting assemblies in a good working order and in good appearance, due to build up of grime, dirt, dust whilst still affording a degree of protection to the mounting assemblies.

The subject application seeks to ameliorate one or more of the abovementioned disadvantages.

SUMMARY OF THE INVENTION

According to one embodiment of the subject application there is provided a mounting means for operatively mounting one or more glass shower door panels to one or more glass or other wall panels, the mounting means including: an elongate guide assembly adapted for receiving and retaining a carriage assembly for mounting a reciprocating glass shower door; and a mounting assembly including one or more end mounting devices for mounting one or more ends of the elongate guide assembly perpendicular to one or more glass panels or walls.

In accordance with another aspect of the subject application there is provided a mounting means for operatively mounting one or more glass shower door panels to one or more glass or other wall panels, the mounting means including: an elongate guide assembly adapted for receiving and retaining a carriage assembly for mounting a reciprocating glass shower door; and one or more spaced guide mounting devices for connecting the guide assembly to an adjacent parallel glass wall panel and spacing the guide assembly a selected distance from and parallel to the adjacent parallel glass wall panel to provide access between the parallel glass wall panel and guide assembly for cleaning.

In accordance with yet another embodiment of the subject application there is provided a mounting means for operatively mounting one or more glass shower door panels to one or more glass or other wall panels, the mounting means including: an elongate guide assembly adapted for receiving and retaining a carriage assembly for mounting a reciprocating glass shower door; and a mounting assembly including one or more end mounting devices for mounting one or more

2

ends of the elongate guide assembly perpendicular to one or more glass panels or walls, and one or more spaced guide mounting devices for connecting the guide assembly to an adjacent parallel glass wall panel and spacing the guide assembly a selected distance from and parallel to the adjacent parallel glass wall panel to provide access between the parallel glass wall panel and guide assembly for cleaning.

Preferably a carriage assembly is provided which includes a friction-reducing vehicle assembly for movement along a guide element associated with the guide assembly.

Preferably the guide assembly includes a housing for sealing and concealing the vehicle assembly which improves running performance, cleanliness and inhibits dirt and dust from collecting in the vehicle/guide element interface. In one embodiment the housing is at least partially cylindrical or an extruded part circle, to provide ease of cleaning to an outside cylindrical face and improved strength and protection for the vehicle assembly mounted therein.

In one embodiment, a cover plate is provided, mounted to the housing along one side, to provide a seal and protection for fastener heads.

The guide element may be in any suitable form, however preferably it includes spaced apart tracks having an intermediate gap therebetween. Lateral retaining means may be provided, in one form being a flange extending upwardly from the tracks to retain the vehicle in the lateral plane.

Preferably the cover plate is arcuate in section and of the same radius as the housing so as to provide a unified cylinder.

Preferably fastening elements are provided with the guide assembly, one fastening element being a threaded or fluted groove on an interior part of the housing, for receiving threaded fasteners at any position along a longitudinal axis of the housing. Apertures may be provided in order to access fastener heads for fastening along opposite walls of the housing.

A clamping block may be provided so as to clamp the guide assembly onto the glass panel or wall. Preferably the clamping blocks are in the form of a cylinder having a threaded recess for receiving a threaded fastener. Side clamps may be provided, as well as end clamps for connecting to, respectively, parallel walls and perpendicular walls. Preferably the side clamps are contoured on one face to receive the housing.

Preferably a stopper is provided to inhibit the vehicle extending past a selected part of the guide assembly.

Preferably the intermediate gap extends to an outside face of the housing so that a portion of the vehicle may extend therethrough for connecting to a door panel. The friction reducing elements on the vehicle assembly may be any suitable form, including skis, sleds, wheels, or any type of rolling bearing assembly. Preferably, there are provided two pairs of rollers for improving stability and for low friction. A connector may extend through the intermediate gap to connect to a clamp for suspending the door panel.

The clamp assembly preferably includes blocks and fasteners, the latter of which pass through an aperture of the glass panel, and is fastened to the blocks for spreading the clamping load to reduce stress on the door panel.

Preferably there are two carriages provided, spaced selected distances along an upper edge of a door panel.

The or each side mounting assembly may include a spacer assembly, which itself includes a spacer element, in one form contoured to support the housing, the contour being, in one form, a concave arc. A clamping block may be provided by having the spacer element on one side of the parallel wall panel and clamping block on the other with a fastener passing through each and tightened up with threaded interface.

An end support assembly may be provided, which includes an end support block, in one form having an offset tag which includes an aperture to retain the end support block in the lateral and longitudinal directions when connected to the housing. A longitudinal aperture may be provided in the end support block to allow a fastener to pass therethrough, when assembled, the fastener passing through an aperture in a perpendicular glass wall panel, and into the clamping block on an opposite side thereof.

It is contemplated that two parallel guide assemblies may be provided so that two frameless glass door panels may be independently moveable to control access to a shower recess. The two guide assemblies would be connected to an end wall at one end and a frameless glass wall panel at another end. Other mounting arrangements may be such that the two guide assemblies mounted parallel to one another between two spaced apart walls of a shower recess.

Still other advantages, embodiments and features of the subject application will become readily apparent to those skilled in the art from the following description wherein there is shown and described a preferred embodiment of the subject application, simply by way of illustration of one of the best modes best suited to carry out the subject application. As it will be realized, the subject application is capable of other different embodiments and its several details are capable of modifications in various obvious embodiments all without departing from the scope of the subject application. Accordingly, the drawings and descriptions will be regarded as illustrative in nature and not as restrictive.

BRIEF DESCRIPTION OF THE DRAWINGS

In order to enable a clearer understanding of the subject application, a preferred embodiment will hereinafter be described with reference to the attached drawings, and in those drawings:

FIG. 1 is an exploded view of a mounting assembly according to a preferred embodiment of the subject application;

FIG. 2 is an exploded view of a mounting assembly according to a preferred embodiment of the subject application particularly showing an end mounting arrangement;

FIG. 3 is an exploded view of a vehicle assembly and guide assembly according to a preferred embodiment of the subject application;

FIG. 4 is an exploded view of a guide assembly and stopper assembly; and,

FIG. 5 is a section view of a housing according to a preferred component of the subject application.

DETAILED DESCRIPTION OF THE PREFERRED EMBODIMENT

Referring to the drawings there is shown a mounting assembly for operatively mounting a frameless glass shower door panel to an adjacent parallel glass wall panel, the mounting assembly generally indicated at 10. The mounting assembly includes a guide assembly 12 which includes a housing 14 for protection and for cleanliness which extends the life of a vehicle assembly 16 (FIG. 3).

Housing 14 is in the form of a part-cylindrical section, extruded to provide a tube 18. Guide elements 24 are provided inside the tube 18, and are in the form of spaced apart tracks 26 and 28, having an intermediate gap 30 therebetween.

Lateral retaining means 32 are provided in the form of an upstanding flange 36, extending from guide elements 26 and 28. The flange 36 maintains the sliding or rolling direction of the vehicle assembly in a longitudinal direction.

Fastening elements are provided in housing 14, in the form of a threaded groove 40 which threadably receives a threaded fastener 42 so as to mount end stopper 44 or end support block 46. Access to fastener 42 is provided through intermediate gap 30.

Other fastening means may be provided by access apertures 48 and 49 so that fastener 43 may access and fasten housing 14 to spacer and clamping blocks 50 and 52 respectively.

10 Arcuate cover plate 54 is provided in order to cover access aperture 48 to provide dust protection, other environmental protection and added strength. Cover plate 54 attaches to housing 14 by enlarged head and tail sections 56 and 58 respectively, which engage with corresponding flanges 57 and 59 respectively. In order to inhibit travel of vehicle assembly 16 past a selected longitudinal point in housing 14, stopper 60 is provided which is in the form of a block 62 having apertures therethrough for receiving fastener 42 which engages with threaded groove 40.

20 End mounting assembly 64 is provided to support end mounting onto glass or other wall panel 65, the assembly including end mounting block 46 mounted to housing 14 via fastener 42 passing through tab 66 and into threaded groove 40. Fastener 41 passes through aperture 47 in end mounting block 46 and wall aperture 67 to be threadably received into clamping block 68 in a similar arrangement to the side clamping arrangement of: fastener 43; arcuate spacer block 50; and threaded clamping block 52.

25 The spacer block 50 is provided to space housing 14 from a parallel glass wall 11 so as to provide cleaning of housing 14 and glass wall 11 between housing and wall.

30 The vehicle assembly 16 includes friction reducing elements 17 mounted on a carriage 19, the friction reducing elements being in the form of two pairs of track engaging wheels 21. 20

35 A connector assembly 23 is provided in order to suspend glass door panel 25. The connector assembly 23 includes clamp assembly 27 which includes clamping blocks 29 and 31 which are clamped via fastener 33 passing through clamping block 31, aperture in glass panel 25 (not shown) and threadably fastening into clamping block 29. Connector element 35 maintains clamping blocks 27 and 29 below housing 14.

40 A pair of vehicle assemblies 16 are provided for each glass panel 25.

45 In operation the housing 14 provides extended life and an extended smooth running of carriage assembly 16 along tracks 26 and 28 by keeping dust, grime and other adverse environmental effects clear of the wheel track interface. The 50 housing, when assembled, is spaced from adjacent parallel glass walls 11, by arcuate spacer 50 to provide cleaning access there between. An aesthetically pleasing finishes also provided thereby.

55 It is contemplated that the guide assembly 12 includes a structural member or is inherently structurally rigid enough so as to span a distance between two end walls 65 and (not shown, but parallel to and spaced from 65, or to mount one end wall 65 adjacent to and perpendicular to one parallel wall 11). This would then mean that no other mounting means or 60 means of support or other frames would be required, which reduces visual clutter.

Finally, it is to be understood that the inventive concept in any of its embodiments are capable of being incorporated in many different constructions so that the generality of the preceding description is not to be superseded by the particularity of the attached drawings. Various alterations, modification and/or additions may be incorporated into the various

constructions and arrangements of parts without departing from the spirit or ambit of the subject application.

The foregoing description of a preferred embodiment of the subject application has been presented for purposes of illustration and description. It is not intended to be exhaustive or to limit the subject application to the precise form disclosed. Obvious modifications or variations are possible in light of the above teachings. The embodiment was chosen and described to provide the best illustration of the principles of the subject application and its practical application to thereby enable one of ordinary skill in the art to use the subject application in various embodiments and with various modifications as are suited to the particular use contemplated. All such modifications and variations are within the scope of the subject application as determined by the appended claims when interpreted in accordance with the breadth to which they are fairly, legally and equitably entitled.

What is claimed:

1. A mounting assembly for mounting a shower door panel relative to an adjacent parallel wall panel, the mounting assembly including:

an elongate guide assembly receiving a carriage assembly supporting the glass shower door panel, the guide assembly allowing reciprocating travel of the carriage assembly in a lengthwise direction within the guide assembly; and

a side mounting device connecting the guide assembly with the parallel wall panel;

wherein the side mounting device includes a first clamping block disposed on a side of the parallel wall panel adjacent to the elongate guide assembly, and a second clamping block disposed on an opposite side of the parallel wall panel;

wherein the first and second clamping blocks are mutually coupled together through the parallel wall panel, clamping the parallel wall panel therebetween and thereby providing a frameless connection of the elongate guide assembly to the parallel wall panel;

wherein the mounting assembly further includes an end mounting device mounting at least one end of the elongate guide assembly with a perpendicular wall panel; and wherein the end mounting device further includes an inner clamping block disposed on a first side of the perpendicular wall panel, immediately adjacent the end of the elongate guide assembly, and an outer clamping block disposed on an opposite side of the perpendicular wall panel; and,

wherein the inner and outer clamping blocks are mutually coupled together through the perpendicular wall panel, clamping the perpendicular wall panel therebetween so as to provide a further frameless connection between the perpendicular wall panel and an end of the elongate guide assembly.

2. The mounting assembly of claim 1, wherein the elongate guide assembly further includes a housing having an inner aperture dimensioned to receive a fastener which is mounted through the inner aperture and serves to interconnect the first and second clamping blocks with the elongate guide assembly whereby the fastener is concealed from view within the housing while the carriage is free to pass through the elongate guide assembly unobstructed by the fastener.

3. The mounting assembly of claim 2, wherein the inner and outer clamping blocks are connected by a second fastener that passes through the perpendicular wall panel.

4. The mounting assembly of claim 1, wherein the first clamping block is configured so as to space the elongate guide assembly a selected distance from the parallel wall panel.

5. The mounting assembly of claim 1, wherein the side mounting device and the end mounting device of the elongate guide assembly provide a structural support to at least one of the parallel wall panel and the perpendicular wall panel.

6. The mounting assembly of claim 1, wherein the elongate guide assembly further includes a first and a second track, spaced apart so as to provide an intermediate gap therebetween for passage of a lower portion of the carriage assembly.

7. The mounting assembly of claim 1, wherein the elongate guide assembly further includes a housing configured to seal and conceal an upper portion of the carriage assembly so as to inhibit dirt and dust from collecting therein.

8. A shower door mounting assembly including:
an elongate guide assembly for enclosing a carriage which carries a sliding door panel, a side mounting assembly connecting the elongate guide assembly to a parallel glass panel, and an end assembly connecting the elongate guide assembly to a perpendicular glass panel;
wherein the side mounting assembly includes a first clamping block disposed on a side of the parallel glass panel adjacent to the elongate guide assembly, and a second clamping block disposed on an opposite side of the parallel glass panel;

wherein the first and second clamping blocks are adapted to be coupled together through the parallel glass panel, clamping the parallel glass panel therebetween and thereby providing a frameless connection of the elongate guide assembly to the parallel glass panel;

wherein the end mounting assembly includes an inner clamping block disposed on a first side of the perpendicular glass panel, immediately adjacent to an end of the elongate guide assembly, and an outer clamping block disposed on an opposite side of the perpendicular glass panel; and,

wherein the inner and outer clamping blocks are adapted to be coupled together through the perpendicular glass panel, so as to clamp the perpendicular glass panel providing a further frameless connection between the perpendicular glass panel and the end of the elongate guide assembly.

9. The shower door mounting assembly of claim 8, wherein the side mounting assembly and the end mounting assembly of the elongate guide assembly provide a structural support to at least one of the parallel glass panel and the perpendicular glass panel.

10. The shower door mounting assembly of claim 8, wherein the first clamping block is configured so as to space the elongate guide assembly a selected lateral distance from the parallel glass panel to enable access therebetween.

11. The shower door mounting assembly of claim 8, wherein a fastener passes through the parallel glass panel to clamp the first and second clamping blocks onto the parallel glass panel.

12. The shower door mounting assembly of claim 11, wherein the elongate guide assembly further includes a housing, the housing further including an inner aperture into which the fastener is, in use, inserted so as to engage with the inner aperture thereby connecting the elongate guide assembly to the first and second clamping blocks.

13. The shower door mounting assembly of claim 11, wherein the elongate guide assembly further includes:
a track for guiding the carriage; and
a housing with an aperture adjacent to the track to receive a fastener to connect the elongate guide assembly to the first and second clamping blocks, wherein the fastener is, in use, concealed from view within the housing, and

such that the carriage is free to move along the track unobstructed past the fastener.

14. A mounting assembly for mounting a glass shower door panel relative to an adjacent parallel wall panel, the mounting assembly including:

an elongate guide assembly receiving a carriage assembly supporting the glass shower door panel, the guide assembly allowing reciprocating travel of the carriage assembly in a lengthwise direction within the guide assembly; and

a side mounting device for connecting the guide assembly with a parallel wall panel;

wherein the side mounting device includes a first clamping block disposed on a side of the parallel wall panel adjacent to the elongate guide assembly, and a second clamping block disposed on an opposite side of the parallel wall panel;

wherein the first and second clamping blocks are adapted to be coupled together with a fastener so as to clamp the parallel wall panel therebetween and thereby provide a frameless connection of the elongate guide assembly to the adjacent parallel wall panel;

wherein the elongate guide assembly further includes a housing having an inner aperture dimensioned to receive the fastener which is mounted through the inner aperture and serves to interconnect the first and second clamping blocks with the elongate guide assembly whereby the fastener is concealed from view within the housing while the carriage is free to pass through the elongate guide assembly unobstructed by the fastener; and

wherein the mounting assembly further includes an end mounting device which mounts at least one end of the elongate guide assembly with an associated perpendicular wall panel.

15. The mounting assembly of claim 14, wherein: the housing further includes an outer aperture provided on an opposing side of the housing to the inner aperture such that the outer aperture is coaxially aligned with the inner aperture, the outer aperture being dimensioned to receive the fastener which is mounted through an inner aperture of the housing and serves to interconnect the first and second clamping blocks with the elongate guide

assembly, whereby the fastener is, in use, passed through the outer aperture to abut the inner aperture such that the fastener is concealed from view within the housing, and such that the carriage is free to pass unobstructed between the outer aperture and the inner aperture.

16. The mounting assembly of claim 14, wherein the elongate guide assembly provides structural support to the at least one of the group consisting of the parallel wall panel and the perpendicular wall panel.

17. The mounting assembly of claim 14, wherein: the end mounting device further includes an inner clamping block disposed on a first side of the perpendicular wall panel, immediately adjacent the end of the elongate guide assembly, and an outer clamping block disposed on an opposite side of the perpendicular wall panel; and, the inner and outer clamping blocks are coupled together through the perpendicular wall panel, clamping the perpendicular wall panel therebetween so as to provide a further frameless connection between the perpendicular wall panel and an end of the elongate guide assembly.

18. The mounting assembly of claim 17, wherein the inner and outer clamping blocks are connected by a second fastener that passes through the associated perpendicular wall panel.

19. The mounting assembly of claim 17, wherein the end mounting device is connected to the elongate guide assembly by a third fastener that passes through a tab extending from the inner clamping block, into an internally longitudinally arranged groove of the elongate guide assembly.

20. The mounting assembly of claim 19, wherein the groove is universally adapted to also receive a fastener for attachment of an end of travel stopper or an end cap.

21. The mounting assembly of claim 14, wherein the first clamping block spaces the elongate guide assembly a selected distance from the parallel wall panel.

22. The mounting assembly of claim 14, wherein the first clamping block is formed integrally with the elongate guide assembly.

23. The mounting assembly of claim 1, wherein the parallel wall panel is formed of glass.

24. The mounting assembly of claim 23, wherein the perpendicular wall panel is formed of glass.
